No. 759,240.

PATENTED MAY 10, 1904.

T. J. CONWAY.

HAMMOCK.

APPLICATION FILED OCT. 24, 1903.

NO MODEL.

UNITED STATES PATENT OFFICE.

THOMAS J. CONWAY, OF NEW YORK, N. Y.

HAMMOCK.

SPECIFICATION forming part of Letters Patent No. 759,240, dated May 10, 1904.

Application filed October 24, 1903. Serial No. 178,319. (No model.)

To all whom it may concern:

Be it known that I, THOMAS J. CONWAY, a citizen of the United States of America, and a resident of the borough of Manhattan, New York 5 city, in the State of New York, have invented a new and useful Improvement in Hammocks, of which the following is a specification.

This invention relates to hammocks for domestic use; and it consists in certain novel features of construction, as hereinafter set forth and claimed.

An objection to hammocks as ordinarily constructed is that they do not give that comfortable position to the body and lower limbs 15 which is necessary to insure perfect relaxation and rest. With the feet upon the hammock a person lying therein on the back is subjected to a strain on that portion of the limbs back of the knees which is very disagreeable and 20 retards the circulation of the blood or causes the limbs to "go to sleep." In order to relax such strain, a man may let his legs hang over the sides of the hammock; but this position is out of the question for women and children and affords only temporary relief.

The leading object of the present invention is to permit the limbs to assume a natural restful position within the hammock itself.

Other objects of the invention are to provide a distinct leg-rest pocket for each foot of the occupant in hammocks intended for men and in all cases to inclose the leg-rest at the foot end of the hammock, so as to prevent the exposure of the limbs of the occupant and to 35 utilize such closure of the foot end of the leg-rest as a sufficient support for its depressed portion, so as to obviate the employment of supplemental supporting devices.

A sheet of drawings accompanies this specification as part thereof.

Figure 1 is a perspective view of an improved hammock, illustrating the present invention. Fig. 2 represents a longitudinal section through one of the leg-rests, and Fig. 3 45 represents an enlargement of a portion of Fig. 2.

Like letters and numbers refer to like parts in all the figures.

The improved hammock comprises a main 50 body portion A, and supports B and C at the

respective ends of said body portion, which may be of any known or approved description.

The body portion A will usually be formed, as heretofore, of a suitable woven fabric, and the supports B and C may consist of the customary ropes, converging to clevises or rings 1 and 2, by which the hammock is suspended. For the purposes of the present invention said body portion A is provided near its foot end with longitudinal oval openings 3 and 4 side 55 by side, beneath each of which a leg-rest D, practically or literally integral with said body portion A, depends. Each of these leg-rests D comprises an inclined bottom portion 5, Fig. 2, merging into and extending downwardly 60 from the surface of the body of the hammock, an end portion 6, substantially at right angles to said bottom portion, and triangular side portions 7, securely united to each other along their adjoining edges. If said leg-rests D be 65 formed mainly by pieces of fabric attached to the main body A of the hammock, as represented in the drawings, longitudinal strips 8 and 9 of said main body portion are preferably and conveniently carried into the leg-rest and 70 securely attached to its main fabric, so as to serve as stays. The edges where the leg-rest D unites with the main body portion A are also preferably and conveniently reinforced by a continuous binding 10, and said bindings are provided at the wider ends of the openings 3 and 4 in the body portion A above the end portions 6 of the leg-rests with elastic stiffeners 11, Fig. 3, of steel, celluloid, or any suitable material, serving as spreaders to keep said 75 openings from closing. By making such spreaders elastic rolling or doubling up the hammock is not interfered with.

By providing a pair of the leg-rests D, as shown in Fig. 1, the occupant of the hammock 80 may be enabled to balance himself or herself in the customary manner, and thus be afforded a sense of as much security as with the feet entirely free.

The opposite end of the main body portion 95 A of the hammock may be provided with an attached pillow E, as shown, or may be finished without such attachment.

There may be but one leg-rest (of double width) instead of two, if preferred, and other 100

like modifications will suggest themselves to those skilled in the art.

Having thus described said improvement, I claim as my invention and desire to patent under this specification—

- 5 1. A hammock constructed with a leg-rest depending from the main body of the hammock and closed at its foot end.
- 10 2. A hammock constructed with a leg-rest depending from the main body of the hammock and closed at the foot end, the whole substantially integral with the main body.
- 15 3. A hammock constructed with a pair of depending leg-rests arranged longitudinally side by side near the foot end of the main body of the hammock and having portions by which the foot end of each is closed.
- 20 4. A hammock constructed with a pair of depending leg-rests closed at the foot end of each, arranged longitudinally side by side near one end of the main body of the hammock and substantially integral with said main body.
- 25 5. In a hammock, a depending leg-rest arranged longitudinally near one end of the main body of the hammock, and comprising an inclined bottom portion extending downwardly from the surface of said main body, and an end portion substantially at right angles to said bottom portion, said end portion serving 30 to close the foot end of the leg-rest.
- 35 6. In a hammock, a depending leg-rest arranged longitudinally near the foot end of the main body of the hammock, and comprising an inclined bottom portion extending downwardly from the surface of said main body and an end portion substantially at right angles to

40 gles to said bottom portion, and provided with longitudinal stays integral with said body portion and attached to those leg-rest portions respectively.

45 7. In a hammock, a depending leg-rest arranged longitudinally near the foot end of the main body of the hammock, beneath an opening in the latter, the edges of said opening being suitably reinforced by a continuous binding.

50 8. In a hammock, a depending leg-rest arranged longitudinally near the foot end of the main body of the hammock, beneath an opening in the latter, said leg-rest comprising an inclined bottom portion extending downwardly from the surface of said main body and an end portion substantially at right angles to said bottom portion, said opening being provided above said end portion with a spreader to keep 55 the same from closing.

55 9. In a hammock, a depending leg-rest arranged longitudinally near the foot end of the main body of the hammock beneath an opening in the latter, said leg-rest comprising an inclined bottom portion extending downwardly from the surface of said main body, and an end portion substantially at right angles to said bottom portion, said opening being provided above said end portion with an elastic 60 spreader to keep the same from closing, substantially as hereinbefore specified.

65 THOS. J. CONWAY.
